INVENTOR

UNITED STATES PATENT OFFICE.

HENRY M. LANE, OF CINCINNATI, OHIO.

BATH-TUB.

1,161,138.

Specification of Letters Patent. Patented Nov. 23, 1915.

Application filed March 8, 1912. Serial No. 682,554. Renewed April 27, 1915. Serial No. 24,346.

To all whom it may concern:

Be it known that I, HENRY M. LANE, a citizen of the United States, residing at Cincinnati, in the county of Hamilton and State 5 of Ohio, have invented certain new and useful Improvements in Bath-Tubs; and I do hereby declare the following to be a full, clear, and exact description of the invention, such as will enable others skilled in the art 10 to which it appertains to make and use the same.

Difficulty is often experienced, especially by invalids, aged persons or children in rising or seating themselves in the modern 15 enamel or porcelain bath tubs. The surfaces of these tubs are naturally slippery and this difficulty is much increased by the presence of water and soap. In order to avoid projections which might be harmful as well 20 as to facilitate manufacture and to preserve a pleasing outline it is very common to use rolled edges which edges, as hitherto constructed, serve to further increase this difficulty.

25 It is the object of my present invention to so construct and arrange the edges and especially the rolled edges of bath tubs as to provide simple, inexpensive and convenient means, whereby a bather may be enabled to 30 use his hands, however soapy and slippery they may be, in aiding himself to change his position in a bath tub. At the same time this is accomplished without providing additional projecting parts so placed as to cause 35 any possible danger of hurting a bather by his striking against them. I accomplish this useful end by providing under the rolled edges finger holds in the form of strengthening ribs which arrest the tendency of the 40 fingers to slip along the edges of the tub.

The invention is shown in a preferred form in the accompanying drawings, wherein—

45 Figure 1 is a side view of a bathing tub provided with my improvement, Fig. 2 is a cross section on the line 2—2 of Fig. 1, and Fig. 3 is a detail of a modification.

The body of the long tub of usual design is shown at 10 and the outwardly rolled edge 50 at 11. I provide ribs 12 preferably under the rolled edge, properly placed and spaced to be convenient for sitting bathers of different sizes. In Fig. 3 the ribs are shown on a straight sided tub. These ribs are pref-

erably cast integral with the tub, and may 55 be produced without cores or other additional labor. In the preferred form they are hidden by the rolled edge and thus offer no modification of design and no protruding parts capable of being accidentally struck 60 by the body.

My invention is broad enough to cover the provision of any resisting surfaces near and under the extreme edges of the rolled over portion of the tub, whether ribs or other 65 formations, whether integrally formed or not, and whether close together or far apart.

In attempting to get aid in rising in a bath tub of ordinary construction by grasping its edge, the hands naturally slip along 70 without resistance, but, by the use of my invention, points of resistance are provided in convenient locations, which catch and arrest the sides of the fingers, thus forming 75 efficient hand holds.

What I claim is—

1. A bath tub having a series of ribs projecting outwardly from its exterior surface near the upper edge thereof in a convenient position to be caught by the fingers when 80 grasping said edge, said ribs having faces set transversely with respect to the side of the tub, substantially as described.

2. A bath tub having a turned over portion and projections on opposite sides of 85 the tub under said turned over portion and near enough to its extreme edge to be caught by the fingers in grasping the edge, substantially as described.

3. A bath tub having a turned over portion and a series of projections under said portion near enough to its extreme edge to be caught by the fingers in grasping the edge, substantially as described. 90

4. A bath tub having a turned over portion and a rib under the same, joining said portion to the main body of the tub, substantially as described. 95

5. A bath tub having a turned over portion, and a series of ribs under the same, 100 joining said portion to the main body of the tub, substantially as described.

In testimony whereof, I affix my signature, in presence of two witnesses.

HENRY M. LANE.

Witnesses:

JOHN J. TAYLOR,
GEO. P. STIMSON.
